CLAIM

The ornamental design for a label sheet with a feed edge assembly, as shown and described.

DESCRIPTION

FIG. 1 is a front view of a first embodiment of a label sheet with a feed edge assembly showing our new design; and, FIG. 2 is a front view of a second embodiment of a label sheet with a feed edge assembly showing our new design. Color and texture may or may not form part of the claimed design without departing from the design disclosed. The inventors anticipate that the invention can be any part, portion, element, or combination of elements of the depicted design. The side, top, and bottom views include a shape and appearance that would be evident from the views of the label sheet with feed edge assembly as shown.
